UNITED STATES PATENT OFFICE.

THOMAS J. BROWN, OF CRAWFORDSVILLE, IOWA.

BOILER FOR TRACTION-ENGINES.

1,097,523.

Specification of Letters Patent.

Patented May 19, 1914.

Application filed October 2, 1912, Serial No. 723,620. Renewed April 14, 1914. Serial No. 831,795.

To all whom it may concern:

Be it known that I, THOMAS J. BROWN, a citizen of the United States, residing at Crawfordsville, in the county of Washington and State of Iowa, have invented certain new and useful Improvements in Boilers for Traction-Engines; and I do hereby declare the following to be a full, clear, and exact description of the invention, such as will enable others skilled in the art to which it appertains to make and use the same.

This invention relates to boilers for traction engines; and it consists in certain pipes provided with valves and connected to the steam space of the boiler at the opposite ends thereof so that dry steam can be obtained irrespective of the level of the ground over which the engine is traveling.

In the drawings, Figure 1 is a side view of the boiler of a traction engine, partly in section, constructed with steam pipes and valves according to this invention. Fig. 2 is a cross-section taken on the line $\alpha-\alpha$ in Fig. 1. Fig. 3 is a partial view similar to Fig. 1, and illustrates a modification of the arrangement of the steam pipes.

The boiler is provided with a shell 2, a fire-box 3, a smoke-box 4, and fire-tubes 5 between the fire-box and smoke-box. All of these parts are of any approved construction. The dotted line 7 indicates the normal water-level when the engine is traveling on level ground. The dotted lines 8 and 9 indicate the water-levels when the engine is traveling up and down a steep hill respectively.

In order to prevent the water from passing from the boiler with the steam when the engine is traveling up-hill or down-hill, a steam pipe 10 is secured longitudinally of the boiler from one end portion to the other and its ends communicate with the steam space at the respective ends of the boiler. An outlet pipe 11 is connected to the intermediate portion of the pipe 10 at any convenient part of its length, and the steam pipe 10 may be formed in sections which are connected together and to the outlet pipe 11 by a T-junction 12.

A valve 14 is provided for closing the front end of the steam pipe 10, and a valve 15 is provided for closing its rear end, each end of the pipe 10 being provided with a suitable valve-seat. The two valves 14 and 15 are connected together by a cou-

pling-rod 16, and an extension of the coupling-rod forms a valve-operating rod 17. A lever 18 is pivoted to the shell of the boiler and is connected to the rod 17, but any other approved means may be used for operating the valve-rod.

The steam pipe 10 is preferably arranged inside the shell of the boiler, and the valve-rod 17 passes through a stuffing-box 19 so that steam from the boiler cannot leak out around the valve-rod. The steam outlet pipe 11 is secured in a hole in the shell of the boiler under and communicating with a steam dome 20, and the steam dome 20 is not placed in direct communication with the steam space of the boiler as in boilers as ordinarily constructed. Condensed steam or water in the steam dome 20 drains back through the pipes 11 and 10. The boiler is provided with a steam regulating-valve or stop-valve 21 of any approved construction.

The valves 14 and 15 are adjusted and secured so that both ends of the steam pipe 10 are open simultaneously when the valves are at their middle positions. When the engine is going up-hill and the valve 15 at the rear end of the pipe 10 is submerged, the valve 15 is closed by hand and the valve 14 is opened, and when the engine is traveling down-hill the valve 14 is closed and the valve 15 is opened. In this manner the steam engine is always supplied with dry steam irrespective of the level of the ground.

In the modification shown in Fig. 3, the steam pipe 10 is arranged outside the boiler, and its end portions are connected to the shell of the boiler by headers 24 and 25 which form extensions of the steam space of the boiler shell. The valve rod 17 is a continuation of the coupling-rod 16, and no levers have to be placed in the steam space of the boiler where they are liable to be injured by deposits of scale from the water, and where they are difficult of access and inconvenient to repair.

What I claim is:

1. The combination with a traction engine boiler, of a steam pipe arranged longitudinally of the boiler with its ends communicating with the steam space, lift valves for closing the ends of the steam pipe, a coupling-rod extending through the steam pipe and having the said valves secured to it, said coupling-rod having an extension which projects from the steam space of the boiler.

and affords a means for operating the valves, and a steam outlet pipe connected to the said steam pipe between its valves.

2. The combination with a traction engine 5 boiler, of a steam pipe arranged longitudinally inside the boiler with its ends communicating with its steam space, lift valves for closing the ends of the steam pipe, a coupling-rod extending through the steam 10 pipe and having the said valves secured to it, said coupling-rod having an extension for operating it which projects through the

end plate of the boiler, a dome provided with a steam outlet and secured to the boiler out of direct communication with its steam 15 space, and an outlet pipe connecting the steam space of the dome with the said steam pipe between its valves.

In testimony whereof I have affixed my signature in the presence of two witnesses. 20

THOMAS J. BROWN.

Witnesses:

NETTIE BROWN,
EDITH HOUGH.
